UNITED STATES PATENT OFFICE.

HENRY R. VAN EPS, OF PEORIA, ILLINOIS.

DESIGN FOR A FLOWER-POT BRACKET.

SPECIFICATION forming part of Design No. 13,905, dated May 15, 1883.

Application filed February 26, 1883. Term of patent 14 years.

To all whom it may concern:

Be it known that I, HENRY R. VAN EPS, a citizen of the United States, residing at Peoria, in the county of Peoria and State of Illinois, 5 have invented and produced a new and original Design for Flower-Pot Brackets, of which the following is a full, clear, and exact specification, reference being had to the annexed drawing, making a part thereof.

10 The figure shows a side perspective view of the bracket.

The essential feature of my design consists of the wire rod bent into the form shown in the drawing, one portion being made circular and 15 fringed with a series of wire loops. The end A of this wire rod is bent vertically, that it may be inserted into eyelets S S, by which to be held and still be capable of horizontal swinging. The other extremity of said wire rod is 20 bent into a circular form, that the loop C thus made shall support a flower-pot. Between said circular loop C and vertical part A is the

shank B, bent in a flattened double curve, so that said loop C shall be relatively higher than said part A. Bent around the circular loop C 25 is a series of fine-wire loops, D D', alternating narrow and wide. Of these the narrow loops D' below the rod C are lengthened and bent horizontally inward toward each other to form a floor upon which to place a flower-pot and 30 its saucer. The wide loops D form the sides to prevent the flower from tumbling off.

I claim—

The design for a flower-pot bracket herein shown and described, the same consisting of 35 a wire rod having circular loop C, curved shank B, vertical part A, and the small wire loops D D', forming side and bottom of said loop C.

HENRY R. VAN EPS.
